FLEXIBLE PULL STRAP FOR AN AERIAL TOY OR THE LIKE

Helmut Karl Bross, Altenberg über Nurnberg, Germany,
assignor of 50 percent to Frank T. Johmann, Berkeley
Heights, N.J.

Filed Apr. 30, 1963, Ser. No. 74,674

Term of patent 14 years

(Cl. D34—15)

FIG. 1

FIG. 2

FIG. 3

FIG. 4

FIGURE 1 is a top view of the pull strap, showing my new design.

FIGURE 2 is a side view of my design.

FIGURE 3 is a sectional view taken along the line 3—3 of FIGURE 1.

FIGURE 4 is a sectional view taken along the line 4—4 of FIGURE 1.

FIGURE 5 is a sectional view taken along the line 5—5 of FIGURE 1.

I claim:

The ornamental design for a flexible pull strap for an aerial toy or the like, as shown.
